CALENDER ROLL

Archibald C. Lade, Easthampton, Mass., assignor
to B. F. Perkins & Son, Inc., Holyoke, Mass.,
a corporation of Massachusetts

Application March 18, 1937, Serial No. 131,620

1 Claim. (Cl. 92—77)

This invention relates to improvements in calender rolls adapted for operating on paper, fabric, and the like.

The principal objects of the invention are directed to the provision of a novel calender roll which is adapted for use in a calender or calender stack in co-operation with another roll or rolls which are similar or have different characteristics and between which rolls a web of paper or fabric 10 may pass.

The roll of this invention is characterized by a more or less yieldable body having a relatively less yieldable outer shell or peripheral part thereby not only obtaining the advantages of both a 15 relatively hard and a relatively yieldable roll but also providing a novel surface which is capable of giving desirable characteristics to the paper or fabric on which it operates.

Various other novel features and advantages 20 of the invention will be hereinafter more fully referred to in connection with the accompanying description of the invention in its present preferred form. In the drawing:

Fig. 1 is a side elevational view of the roll embodying the novel features of the invention;

Fig. 2 is a sectional elevational view on the line 2—2 of Fig. 1.

Referring now to the drawing more in detail the invention will be fully described.

The roll of the invention has a central shaft 2 and end members 6 secured thereon in some suitable manner. Between the flanges there is a body 4 formed from sections or discs which are held in pressed-together relation by the end members 6.

The end members 6 may be held or locked on the shaft 2 by any suitable means. The degree of pressure may, of course, be varied for different purposes.

The discs or sections for the body are formed from fibrous material preferably from fabric, and these have openings therethrough for the shaft. To prevent the discs or sections forming the roll body from turning on the central shaft, there 45 may be keys 8 or the like receivable in splines in the discs.

The discs 10 as stated and illustrated in Fig. 2 are preferably formed of some more or less yieldable material and fabric has been found to be suitably adapted for the purpose of the invention.

The discs adjacent their periphery have portions that are impregnated or treated with some material which in the finished roll is relatively 55 more rigid or less yieldable and resilient than

inner portions of the discs. To that end some plastic such as a phenolic resin or phenolic condensation product has been found to be satisfactory.

As a good example the outer peripheral portion of the discs have been treated with a substance known as Bakelite. The fabric has been treated or impregnated with this material and suitably cured or processed to harden the plastic. In this way each disc or section of the roll has a 10 relatively hard non-yieldable peripheral portion 12 about a more yieldable body portion 14 which surrounds the central shaft.

The discs or sections described are arranged in stacked relation on the shaft and pressed together and confined in their pressed-together relation by the members 6, whereby there is provided a roll body having a more or less rigid or hard peripheral portion 14 with a less rigid and more yieldable inner portion 12 about a rigid 20 shaft. The peripheral surface of the roll is worked down to the desired diameter and surface by grinding, turning, or some other suitable operation.

The roll body formed as described thus has a 25 relatively yieldable portion around the central shaft and a relatively harder more rigid or less yieldable outer layer or shell. It also has a novel peripheral surface in that it is composed of fibrous material and the plastic medium whereby 30 the roll is capable of performing operations not heretofore known in the art.

The roll of the invention may be employed in some instances adjacent a metal roll or it may be employed in cooperation with a similar roll, or 35 a laminated roll of some other form depending upon the use to which the roll is to be employed.

It will be observed that the surface of the roll is unique in that it is not necessarily entirely of either fibrous or plastic material; that is, it is 40 not composed entirely of either the more rigid substance or the yieldable material, but it is a combination of those two substances. By varying the amounts of the harder plastic various results may be obtained. The surface of the roll is 45 backed up by the relatively rigid layer or shell of the roll which surrounds the less rigid central part all to the end that the roll has the characteristic of a hard roll and the resiliency and yieldability of a relatively rigid roll.

While I have described the invention in great detail and with respect to a preferred form thereof, it is not desired to be limited thereto since many changes and modifications may be made therein without departing from the spirit and 50 55

scope of the invention. What it is desired to claim and secure by Letters Patent of the United States is:

A calender roll of the class described comprising in combination, a rigid, central shaft, disc-like members disposed in adjacency on said shaft, said disc like members being formed of fibrous material and having their outer peripheral portions impregnated with hardened plastic mate-

rial, and means holding said members in tightly-pressed roll-forming relation on said shaft whereby they present a substantially rigid and unitary peripheral portion having a substantially hard peripheral surface and the roll has a relatively less hard and resilient area around said rigid shaft.
